(57) **CLAIM**

I claim the ornamental design for a baluster, as shown.

DESCRIPTION

FIG. 1 is an isometric view from slightly above a first embodiment of the baluster, showing a first and second side of the baluster.

FIG. 2 is a lateral view of a first side of the first embodiment of the baluster.

FIG. 3 is a lateral view of a second side of the first embodiment of the baluster.

FIG. 4 is a lateral view of a third side of the first embodiment of the baluster.

FIG. 5 is a lateral view of a fourth side of the first embodiment of the baluster.

FIG. 6 is a plan view of the top of the first embodiment of the baluster.

FIG. 7 is a plan view of the bottom of the first embodiment of the baluster.

FIG. 8 is an isometric view from slightly above a second embodiment of the baluster, showing a first and second side of the baluster.

FIG. 9 is a lateral view of a first side of the second embodiment of the baluster.

FIG. 10 is a lateral view of a second side of the second embodiment of the baluster.

FIG. 11 is a lateral view of a third side of the second embodiment of the baluster.

FIG. 12 is a lateral view of a fourth side of the second embodiment of the baluster.

FIG. 13 is a plan view of the top of the second embodiment of the baluster; and,

FIG. 14 is a plan view of the bottom of the second embodiment of the baluster.
